OF ATLANTA, GEORGIA

TIRE LOCK.

15,282.

Specification of Reissued Letters Patent. Reissued Feb. 7, 1922.

Original No. 1,370,977, dated March 8, 1921, Serial No. 213,619, filed January 24, 1918. Application for reissue filed August 15, 1921. Serial No. 492,507.

To all whom it may concern:

Be it known that I, HENRI G. LEVY, a citizen of the United States, residing at San Francisco, in the county of San Francisco and State of California, have invented a new and useful Tire Lock, of which the following is a specification.

This invention relates particularly to means for locking vehicle tires onto vehicle wheels or onto tire racks or other mountings.

Among the objects of the invention are to prevent the theft, particularly of pneumatic tires, from automobile wheels or from their carrying racks, and to provide such a lock as will be adaptable to the present construction and arrangement of pneumatic tires on permanent or demountable rims, to prevent the theft thereof from the vehicle wheels or the spare tires carried on suitable carriers.

With the above objects in view the invention consists generally of a novel combination of elements subsisting among the tire, its mounting which is provided with means for holding the tire, a stem such as the valve stem which projects through said mounting and has means at its inner end for co-operation with the mounting to secure the tire, and the locking element which is fitted to the stem and co-operates therewith and with the mounting to provide a positive lock which can not be manipulated by an unauthorized person and which will prevent the theft of the tire from its mounting under any condition of inflation or deflation; the invention also consists in novel details of structure and arrangement appurtenant to such combination.

In this specification and the annexed drawings, the invention is illustrated in the form considered to be the best, but it is to be understood that the invention is not limited to such form, because it may be embodied in other forms; and it is also to be understood that in and by the claims following the description, it is desired to cover the invention in whatever form it may be embodied.

In the accompanying one sheet of drawings:

Figure 1 is a side elevation, partly in cross section, of a tire lock constructed in accord-

ance with this invention and applied to a vehicle wheel and tire shown in cross section. 55

Fig. 2 is a plan view from above of the valve stem engaging lock, in the closed position.

Fig. 3 is a similar view of the same showing the lock in the open position with the valve stem shown in cross section therein.

Fig. 4 is a front elevation of a modification of the locking means.

Fig. 5 is a plan view from above of the same, illustrating a pad lock having a spring 65 bow engaging a tire valve shown in cross section.

In detail the construction illustrated in the drawings includes, referring to Fig. 1, the tire casing 1 mounted on the conventional rim 2 which is fixed, or demountably attached, to the felly 3, of the vehicle rim and which includes flanges 2^a for holding the tire. The tire casing has the usual inner air tube 4, provided with the valve stem 5 fixed therein and extending through the rim 2 and the felly 3 through which it protrudes. This valve is threaded throughout its length to receive the jam nut 6, which holds the spreader 7 and the washer 8 and the wall of 80 the inner tube 4, in compressed assembly against the head 9 of the valve stem, the spreader co-operating with the rim and its flanges 2^a to secure the tire to the rim. The running nut 10 provided with an internal 85 compression washer (not shown), in the usual manner, is threaded on the valve stem and bears against the felly to cover the hole therethrough for the passing of the valve stem. Thus far the construction is conventional and is encountered with various modifications in this art. 90

The locking device as illustrated in Figs. 1, 2 and 3, comprises a lock 11, preferably of the pad lock type, having the bow 12 95 with the extensions 13 and 14 extending into the pad lock to be engaged by the locking bolt controlled by the removable key 15. The opening 16 between the interior of the bow and the end of the padlock is of a contour to fit snugly the perimeter of the valve stem which consists of a circle having flattened sides 17 and 18 to engage the flat side of the valve stem, extensions 19 and 20 of the circle being threaded to engage the thread 105 on the valve stem to prevent the pad lock

from being moved longitudinally on the valve stem. The lock 11 and the bow 12 are each provided with the semicircular lugs 21-22, which combined form a true circle having an annular groove therein to engage the annular flange 23 formed on the dust cap 24, which is in the form of a tubular thimble entirely inclosing the end of the valve stem 5. The valve stem is provided 10 with an interior spring operated check valve (not shown) to hold the air pressure pumped into the inner tube 4. The end of the valve stem being reduced and threaded to receive the valve cap 25 provided with a gasket to 15 seal the end of the valve stem, in the usual manner.

This invention operates substantially as follows: The padlock in the open position, as shown in Fig. 3, is inserted over 20 the protruding end of the valve stem to a position at rest on top of the nut 10, the dust cap 24, the neck 26 of which need not be threaded, clears the threads on the valve stem and is inserted over the end of the 25 valve stem inclosing the valve cap. The padlock is then closed, and its parts locked together to co-operate with the stem 5 and the tire mounting in positively locking the tire to the mounting and, in the embodiment 30 disclosed, to engage the flange 23 on the dust cap. The bow 12 automatically locks if the construction be what is known as a snap padlock or if otherwise constructed said bow may be locked by the turning of 35 the key which is then removed. Thus applied this locking device co-operates with the valve stem and the tire mounting, positively and securely to lock the tire 1 on the felly 3 and to prevent its removal until the 40 removal of the padlock 11. The particular reason for locking the dust cap 24 in position is to prevent the deflation of the tire by the removal of the valve cap 25 and the unseating of the valve in which manner the 45 air could be removed noiselessly and without causing suspicion. On the other hand, if the valve stem were broken off while the tire was inflated, the sudden rush of air from the valve would cause a whistling 50 noise giving warning that the tire was being tampered with, which in itself would act as a deterrent to the ordinary petty larcenist. It is obvious that the application of this lock in no way interferes with the normal 55 functioning of the parts to which it is attached.

In Figs. 4 and 5 is illustrated a modification of the lock, in which the reduced neck 27 is threaded to engage the thread on the 60 valve stem 5, as is now common practice. The end of the dust cap is notched as at 28 to engage the lug 29 formed on the lock 30. This lock 30 is similar in every way to the lock 11 except that it is unnecessary to 65 thread the bow 31 and the end of the lock as

at 19 and 20 shown in Fig. 2, but the contour of the bow and the end of the padlock are made to snugly engage the perimeter of the valve stem. The lug 29 engaging the notch 28 prevents the unscrewing of the 70 dust cap because of the non-rotatable engagement of the padlock with the valve stem. The bow 31 is locked by the removable key 32. The bow may be of the sliding type 75 illustrated in Figs. 2 and 3, or may be pivoted as at 33, to swing out of engagement with the valve stem. The particular form of the lock is not germane to this invention and may be varied to suit circumstances or 80 the taste of the producer.

In Fig. 4 the annulus 34 of the tire rack is indicated to show the application of the lock to tires carried on the rack, inflated ready for application to the vehicle wheel. The mode of operation of the lock in either 85 instance is the same, except that the lock 30 lies against the annulus 34 instead of against the felly of the wheel or the nut 10.

Having thus described this invention, what I claim and desire to secure by Letters Patent is:

1. In combination, an inflatable vehicle tire having an inflating valve provided with a dust cap, a felly through which said valve projects, and a lock adapted to bear against 95 the felly and to engage the dust cap and comprising two complementary members having semicircular portions to form a circular opening adapted to receive the valve below the dust cap thereof, said opening having 100 at least one flattened surface to engage a corresponding surface on the valve, at least one of the members having means engageable with the lower portion of the dust cap to prevent an axial movement thereof relative to the valve, and a key controlled locking means for securing said members in and releasing them from effective locking position.

2. In combination, an inflatable vehicle 110 tire having an inflating valve provided with a dust cap, a felly through which said valve projects and a lock adapted to bear against the felly and to engage the dust cap and comprising two complementary members having threaded circular portions adapted to form a circular opening to receive the valve below the dust cap thereof, said opening having at least one flattened surface to engage a corresponding surface on the valve, at least one of said members having a rigid 115 detent engageable with the lower portion of the dust cap to prevent an axial movement thereof relative to the valve, and a key controlled locking means for securing said members in and releasing them from effective locking position.

3. In combination, an inflatable vehicle 120 tire, a mounting therefor having means for holding the tire, a stem carried by the tire 125

- and projecting through the mounting, said stem having at its inner end means for co-operation with the mounting in securing the tire thereto, and a device formed 5 to fit over the projecting portion of the stem and having means for locking it against endwise and turning movement relative to the stem, said device thereby co-operating with said stem and mounting in positively 10 locking the tire to the mounting.
4. In combination, an inflatable vehicle tire, a mounting therefor having means for holding the tire, a stem carried by the tire and projecting through the mounting, said 15 stem having at its inner end means for co-operation with the mounting in securing the tire thereto, and a device formed to fit over the projecting portion of the stem and to engage the stem against endwise and turning 20 movement and having means by which it may be locked in such position, said device thereby co-operating with said stem and mounting in positively locking the tire to the mounting.
5. In combination, an inflatable vehicle tire, a mounting therefor having means for holding the tire, a stem carried by the tire and projecting through the mounting, said stem having at its inner end means 25 for co-operation with the mounting in securing the tire thereto and having its projecting portion formed with threads interrupted by flat faces, and a device formed to fit over the stem and to engage said 30 threads and flat faces, said device having 35 means for locking it in such engaged position and thereby co-operating with said stem and mounting in positively locking the tire to the mounting.
6. In combination, an inflatable vehicle 40 tire, a mounting therefor having means for holding the tire, a stem carried by the tire and projecting through the mounting, said stem having at its inner end means for co-operation with the mounting in securing the 45 tire thereto, and a device formed to fit over the projecting portion of the stem and having means for locking it against endwise movement relatively to the stem, said device thereby co-operating with said stem 50 and mounting in positively locking the tire to the mounting.
7. In combination, an inflatable vehicle 55 tire, a mounting therefor having means for holding the tire, a stem carried by the tire and projecting through the mounting, said stem having at its inner end means for co-operation with the mounting in securing the tire thereto, a device formed to fit over the projecting portion of the stem, and having 60 means for locking it against endwise movement relatively to the stem, said device thereby co-operating with said stem and mounting in positively locking the tire to the mounting, and a dust cap secured by 65 said device as locked in operative position on said stem.

In testimony whereof, I affix my signature.

HENRI G. LEVY.
